UNITED STATES PATENT OFFICE.

WILLIAM G. KECK, OF KECKSBURG, PENNSYLVANIA.

DESIGN FOR A BOTTLE OR SIMILAR ARTICLE OF MANUFACTURE.

Application filed May 19, 1927. Serial No. 22,101. Term of patent 14 years.

To all whom it may concern:

Be it known that I, WILLIAM G. KECK, a citizen of the United States, residing at Kecksburg, in the county of Westmoreland and State of Pennsylvania, have invented a new, original, and ornamental Design for Bottles or Similar Article of Manufacture.

I claim:

The ornamental design for a bottle or similar article of manufacture, as shown.

WILL. G. KECK.
